ATTORNEY

WITNESS:

D. Frank.

UNITED STATES PATENT OFFICE

RALPH CAIAZZO, OF BROOKLYN, NEW YORK, ASSIGNOR, BY DIRECT AND MESNE ASSIGNMENTS, TO AMERICAN NEW FASHION SILVERWARE CORPORATION, OF BROOKLYN, NEW YORK, A CORPORATION OF NEW YORK

SHOE-HEEL DEVICE

Application filed September 6, 1929. Serial No. 390,762.

This invention relates to improvements in ladies' shoe heels and its leading object is to provide a composite shoe heel lift which can be attached to the standard wooden heel of a lady's shoe, and which will be attractive in appearance, wear resistance in use, and attached firmly by small nails to the wooden base or heel, so that it will resist accidental detachment for a long period.

10 Another object of the invention is the provision of a shoe heel lift for a lady's shoe, which, having a base formed of metal and providing a socket for the lower end of a wooden shoe heel, includes also penetration 15 resisting portions through which nails are driven, and a lift retaining marginal portion for holding a leather lift in place, so that this marginal portion forms a non-slipping means and also provides an external metal surface 20 to present an attractive decorative appearance.

Other objects and advantages of the invention will be hereinafter specifically pointed out, or will become apparent, as the specification proceeds.

With the above indicated objects in view, the invention resides in certain novel construction and combination and arrangement of parts, clearly described in the following 25 specification and fully illustrated in the accompanying drawings, which latter shows an embodiment of the invention as at present preferred.

In the drawings:—

25 Figure 1 is a view in perspective showing the invention applied to a heel of a lady's shoe.

Figure 2 is a plan view of the heel lift, detached, on an enlarged scale.

30 Figure 3 is a side elevation of the improved heel, on an enlarged scale.

Figure 4 is a bottom plan view thereon, on an enlarged scale.

Figure 5 is a vertical sectional view, also 45 on an enlarged scale.

Referring to the accompanying drawings illustrating the practical embodiment of the invention, 5 designates a heel of a lady's shoe, which is constructed according to current 50 practice, and which has a lift carrying lower

face 5', against which the improved composite heel lift 6 is mounted.

This composite heel lift includes the metal shell or endless band 6a and the leather or yieldable insert 6b.

The shell is formed by casting, die casting or otherwise, by die pressure shaping, or by any method convenient or best adapted to produce the required special construction, which includes a heel socket, to receive the lower end of the wooden shoe heel. This socket is made up of the curved wall 6d, which has a form corresponding to that of the base of the wooden heel and is designed to snugly fit the same. This wall is relatively low, so that the socket will be shallow. Within this encircling and heel reinforcing wall is an integral web 6e, which is approximately crescent shaped, but provided with a central inwardly offset portion 6e'.

This web receives the thrust of the shoe heel and also provides means for anchoring the lift to the wooden shoe heel, as it is formed with a series of small nail openings 6f, spaced apart in the web and in its offset portion.

Against the underside of the web 6e the leather shoe lift insert 6b is placed. This lift completely covers the web and is retained against the web by means of the integral skirt or flange 6h, which is shown to be slightly flared outwardly, and which is also formed with inturned retaining teeth 6i, which are crimped against the edges of the leather lift insert, so as to retain the same under compression against the web 6e.

The retaining nails 7 are forced through bores 7a formed in the leather lift insert thence through the openings in the web and into the wooden shoe heel until the heads of the nails engage the underside of the web 6e, so that the nails securely fasten the composite lift to the shoe heel as clearly shown in Figure 5 of the drawings.

The infolded teeth 6i extend in a curving line which is co-extensive with the outer edge of the leather lift insert, and provide non-slipping means for enabling the user to safely walk upon dangerous pavements.

The flare of the retaining flange, which forms a skirt for the leather lift insert, also

allows the flange to burr slightly under the thrusts developed in walking, and this action will serve to maintain the leather lift in its pocket within the flange, after the crimped and infolded teeth have been worn away.

The socket on the upper side of the composite heel lift prevents the wooden shoe heel from slipping or chipping, and also protects its fabric or leather covering from peeling and becoming unsightly.

The wall 6d is provided on its external face with a series of line ridges or beads such as indicated by the reference numeral 6c, and these ridges or beads are adapted to give the lift a decorative or ornamental effect, and while I have shown ridges or beads, it will be obvious that grooves may be provided as well as ornamental design work such as indicated at 6h.

The infolded teeth 6i which form the lower marginal edge of the slightly flaring skirt or flange 6h, also add to the attractive appearance of the composite lift, so that the visible external face of the metal backing is such as to really trim the general appearance of the wooden heel, in addition to reinforcing it.

The lower part of the wooden shoe heel may be reduced so that the external face of the composite lift will be flush with the external face of the wooden shoe heel. The metal backing may be made from any metal or alloy of metals, but a light color brass, plated with a protecting coat of other metal, has been found to give good service, and to heighten the general appearance of the shoe equipped with the improved composite lift.

The area of the web is less than the area of the space which contains the leather lift insert, so that a small cushioning space is left between the insert and the wooden heel.

The hereinbefore described construction admits of considerable modifications without departing from the invention; therefore, I do not wish to be limited to the precise arrangements shown and described, which are, as aforesaid, by way of illustration merely. In other words, the scope of protection contemplated is to be taken solely from the appended claims, interpreted as broadly as is consistent with the prior art.

I claim as new:

1. A composite shoe heel lift comprising a shell, a web disposed in said shell to provide a shoe heel receiving socket, an outwardly flared skirt included in said shell and disposed below the web, a yieldable insert disposed in the skirt, and teeth formed with the lower edge of said skirt and being engageable with the bottom of the insert to secure the latter within the skirt, and said web being substantially crescent shape in formation so as to form a pocket between the shoe heel and insert.
2. A composite shoe heel lift, comprising a

shell, a web arranged in said shell to provide a shoe heel receiving socket including a wall following the shape of the heel, a skirt depending from the wall and being outwardly flared, an insert disposed in said skirt and following the shape thereof, and teeth formed with the lower edge of said skirt and being bent for contacting engagement with the bottom of said insert for securing the latter within the skirt and against the web, said web having openings therein and being of a shape to provide a pocket between the insert and shoe heel, and said insert having bores therein aligned with the openings and said openings and bores adapted to receive headed securing means with the heads thereof seated against the web.

In testimony whereof I hereby affix my signature.

RALPH CAIAZZO.
